UNITED STATES PATENT OFFICE.

SAMUEL J. COX, OF LIMA, OHIO.

ADJUSTABLE WINDOW-SHADE HANGER.

SPECIFICATION forming part of Letters Patent No. 642,815, dated February 6, 1900.

Application filed July 7, 1899. Serial No. 723,112. (No model.)

To all whom it may concern:

Be it known that I, SAMUEL J. COX, a citizen of the United States, residing at Lima, in the county of Allen and State of Ohio, have invented certain new and useful Improvements in Adjustable Window-Shade Hangers, of which the following is a specification.

My invention relates to improvements in adjustable window-shade hangers; and one object of my invention is the provision of a hanger which will allow the shade to be held at any adjustment with relation to the window-sash.

Another object of my invention is the provision of an efficient and thoroughly practical means whereby the shade and hanger are adjusted and which is very simple, durable, and inexpensive.

To attain the desired objects, the invention consists of an adjustable window-shade hanger embodying novel features of construction and combination of parts, substantially as disclosed herein.

Figure 1 is a perspective view of a window and sash with my invention in operation thereon, and Fig. 2 is an enlarged plan view of the upper member of my invention.

In the drawings, A designates one section of the upper member, which is secured to the window-casing by any well-known means, such as screws, and B the other section, the section A being provided with the bent end C, in whose loop is journaled the pulley D, and the section B being provided with a bent end E, which is out of line with the bent end C, and secured to the section B and adapted to divide the loop formed by the bent end is the plate or division-wall F, said division-wall being held in place by means of the lip G and the axles H and H', which secure the wall rigidly in place. Journaled upon the axle H is the outer pulley J, and upon the axle H', upon either side of the division-wall, are journaled the pulleys K and K'. Upon the inner ends of each section are rigidly secured the bands L, which are adapted to brace the sec-

tions and hold them together at any adjustment, and when the adjustment has been reached the upper member is secured in place to the window-sash. The lower member consists of the sections M, each of which is provided with the shade-supporting lugs or projections N and the similar bands O, which are secured to the inner ends of the sections, and as one of them is provided with the set-screw P the section can be held rigidly at any desired adjustment.

Secured in the openings Q in the sections M are the ends of the cord R, one portion of which passes upward from one opening over the pulley D and the pulley K', while the other portion of the cord passes over the pulley J and over around the pulley K, this cord then being attached to a pull-cord S, which may employ any fastening means to hold the lower member at its proper height.

From this description it will be seen that I provide an adjustable window-shade hanger which is adjustable to any width window and which may be raised or lowered to accommodate any length of window-frame, thus producing a simple, durable, and cheap article of this character.

I claim—

The herein-described window-shade hanger, comprising the upper member made in two sections and adjustably held together, pulley-casings formed by the bent ends of said sections, one end having a division-wall located between the bent end and body of the member, two pulleys journaled in the space between the body and wall and one pulley journaled in the space between the bent end and the wall, and a shade-carrying member adjustably supported by means of said pulleys and the upper member.

In testimony whereof I affix my signature in presence of two witnesses.

SAMUEL J. COX.
